UNITED STATES PATENT OFFICE

HENRY A. WISE WOOD, OF NEW YORK, N. Y., ASSIGNOR TO WOOD NEWSPAPER MACHINERY CORPORATION, OF NEW YORK, N. Y., A CORPORATION OF VIRGINIA

SHEET-INSERTING MECHANISM FOR PRINTING PRESSES

Application filed April 6, 1926, Serial No. 100,082. Renewed January 17, 1930.

The principal object of the invention is to provide for the production of printed products which have a number of pages, not in multiples of four, and specifically to obtain 5 a ten or fourteen page paper on a press that would ordinarily not be capable of producing such a product. This is done with the addition of a narrow supplement press and with a small addition to the folding device. The 10 machine can be run with the supplement press operating at half or full speed for different purposes. Other objects and advantages of the invention will appear hereinafter.

Reference is to be had to the accompanying drawings in which

Fig. 1 is a side view, diagrammatic in form, of a thirty-two page press and folder with the addition of a supplement press illustrating a plant to which this invention is 20 applicable;

Fig. 2 is an end view of a folder arranged to co-operate with the press shown in Fig. 1 for carrying out this invention;

Figs. 3 to 7 are diagrammatic views showing the folding and collecting operation in which the supplement is folded on the outside of two regular newspaper sections;

Fig. 8 is a perspective view of the product thereof;

Figs. 9 to 13 are corresponding diagrammatic views showing the introduction of the supplement between the two sections;

Fig. 14 is a view similar to Fig. 8 showing this product; and

Figs. 15 and 16 are diagrammatic views of a modified arrangement showing another means for accelerating the feed of the supplement to the folder and showing the parts in two positions.

Referring first to Fig. 1, in this case there are two main presses 10, each capable of producing a sixteen page newspaper or part thereof. There is also a supplement press 11 at the end of the same and coupled up at 12 with the driving shaft for the press which in this instance is shown as a straight line drive. Through gearing 13 this supplement press can be driven at the full speed of the presses 10 or at half speed in accordance with the 45 gear changes. This supplement press is

capable of delivering four pages of printed matter to a revolution in the shape of a web one page wide. When this press is driven at full speed by coupling this shaft directly to the press shaft at the coupling 12 or by 55 using equal size gears 13, four additional pages are provided for the main product of the press per revolution. In this case the web 14 from the supplement press is led over and above the regular webs 15 of the press 60 and it is directed to the folder in the same way as the regular webs. It is turned over a turning bar 16 placed directly above the former in the folder so as to present its web in the line with the others within the folder. 65

The supplement web 14 can be directed to the right or to the left as shown in dotted lines in Fig. 2. In this case the supplement web will be fed together with the web or webs coming from the former into the regular nipping rolls 17, between the folding cylinder 18 and the cutting cylinder 19 to the folding rolls 20, fan 21, and delivery belt 22 in the usual way. In this instance, without any addition to the folder, two unfolded pages are added to each non-collected product and the work comes through in the usual way without any additional features except the supplement press and the turning bars. 70

The rest of the drawings are devoted to showing the use of the invention in making collected products. The supplement press is run at half the speed of the main press. When driven in this way only two pages are added at each revolution of the main press, 85 thus producing the ordinary product of the press with two additional pages. As alternate products are duplicates of each other, it would be undesirable to insert a two page addition into every alternate noncollected 90 product.

It is of course necessary to provide gearing 13 for cutting down the speed of the press 11 to exactly half the speed of the other presses. Furthermore the product of 95 the half speed web is cut into sheets and these sheets have to be accelerated from half speed to full speed so that they may be interfolded with the regular papers delivered at full speed from the main press. 100

For this purpose I add a pair of cylinders to the folder, a carrying cylinder 22 and a cutting cylinder 23 exactly like the cylinders 18 and 19 except that the cylinder 22 is provided with notches 24 for receiving the cutters on the cylinder 19 and it has no folding mechanism. These cylinders 22 and 23 are run at the same ratio with respect to each other as the cylinders 18 and 19 but at half their actual speed. The nipping rollers 25 also are run at half the speed of the nipping rollers 17. Ordinary gearing for producing these speeds is employed and this unit is run otherwise in the same way as the usual unit. The web 14 is fed through the nipping rollers 25 and between the cutting and carrying cylinders 23 and 22 where it is cut into sheets and carried around by the cylinder 22 by means of pins thereon.

In Fig. 3 I have shown the web 14 as being advanced between the two cylinders 22 and 23 running at half speed. One sheet 14^a is shown here as having been taken half way around the cylinder 19. When the head of that sheet reaches the full speed cylinder 19, the pins on that cylinder impale the half sheet near the end and take it around with it at an accelerated speed, that is full web speed. The web or webs 15 meet it there and the two advanced ends proceed together further around the cylinder 19. This web 15 of course has been through the former and doubled over.

The next stage in the operation is shown in Fig. 4. Here the sheet 14^a which formerly came from the cylinder 22, as well as the sheets coming from the former, are advanced another half revolution on the cylinder 19. The sheet 14^a surrounds that cylinder and the sheets from the former extend half way around it. The web 14 is further advanced around the cylinder 22 by this time.

Fig. 5 shows the advance of the cylinder 19 another half revolution in which it has the sheet 14^a exactly surrounding and next to it and a set of sheets from the former also surrounding it outside the sheet 14^a. In other words, they are collected on top of it.

At this point, the pins in the cylinder 18 pick off from the cylinder 19 both of the signatures wrapped around the latter as well as the incoming signature and carry all three down around it as shown in Fig. 6. Then this product is folded off into the folding rollers 20 ready to be carried through them as shown in Fig. 7. It will be noticed that in Fig. 7 the action of the cylinder on the half speed sheet coming from the supplement press is shown. The parts here are in the same position as in Fig. 3 and the operation described in connection with these four figures is just starting over again.

The product of this operation is shown in Fig. 8. This product consists of a two page sheet 14^a on the outside of the two regular

newspaper sections 26 all folded to half page size.

The two page sheet 14^a can be pasted to its adjacent section by means of a paste pot 27 and roller 28 which will place a line of paste along the sheet so that in folding it will be pasted to the sheet that comes on that side. 70

In Figs. 9 to 13 the corresponding positions are shown when it is desired to collect the two page sheet 14^a between the two sections from the main press instead of on the outside. It is thought not to be necessary to describe these figures in detail as it will be obvious that the sheet from the main press, that is, the web 15, is wound around the cylinder 19 first and its advance edge is met by the sheet 14^a as shown in Fig. 10. These two are then carried around another half revolution of the cylinder 19 and the web 15 is cut. The next section from that web is then wound on the cylinder 19 as shown in Fig. 11 and carried down to the folder in a continuous motion as shown in Figs. 12 and 13. The product is shown in Fig. 14. 85

This merely shows another way of operating the same mechanism. This mechanism provides for adding two pages to any product of a semicylindrical press but it also insures the association of the two page sheet with the regular product in absolute register. This is due to the accuracy of the folding and collecting on this mechanism. It is not necessary therefore to trim or cut off the edges and no paper dust is collected and accumulated. Heretofore efforts to add a supplement of less than the regular number of pages have generally been accompanied by a serious lack of register, the congregation of paper dust, and commonly the necessity of the throwing out the white unprinted sheet which had to be run in and then eliminated in order to retain two pages from a normal four page product. 100

I also show in Figs. 15 and 16 another arrangement by which a half speed sheet can be accelerated. In this case the cylinders 18, 19, 22 and 23 are employed and there is not much change in any of them except the cylinder 22. This is provided with sectional pin carriers 30 which are pivoted on the shaft of the cylinder 22 and held in place by springs 31. There is a slight change in the cylinder 19 as it has a lug 32 which engages a projection 33 on the pin carrier once during each revolution of the cylinder 19. This swings forward the pin carrier and with it the incoming sheet 14^a. This is accomplished during the transfer of the preceding sheet from the cylinder 22 to the cylinder 19 which is of course running at full speed. In this way the sheets 14^a are brought up to full speed before they are transferred to the pins on the cylinder 19. The spring 31 brings the pin carrier 30 back against a stop 34. 110 120 125

In this way I can employ the product of a semi-cylindrical 16 page press and secure 130

from it with the aid of the supplement press a ten or fourteen page paper and in fact I can vary the product of the ordinary press now on the market practically at will, not being limited to anything except to have an even number of pages, which is practically no limitation at all in this industry.

Although I have illustrated and described only two forms of the invention and shown only two different ways of operating it, I am aware of the fact that other modifications can be made therein by any person skilled in the art without departing from the scope of the invention as expressed in the claims.

Therefore, I do not wish to be limited to all the details of construction herein shown and described, but what I claim is:

1. The combination with a printing press and its folder, of a supplement press arranged to deliver four pages on a web one page wide at each revolution, means for connecting the supplement press to the main press to run at full or half speed, a former delivering to the folder, means for directing both products to the folder over the former when running the supplement press at full speed, and means for directing the product of the supplement press to the folder without passing over the former when running at half speed to collect each printed product with a two page supplement therefrom.

2. The combination with a folder having a cutting and a collecting cylinder and a folding cylinder, of two similar cylinders adjacent thereto, and means for running the second pair of cylinders at half the speed of the first pair of cylinders, said two pairs of cylinders being arranged to cooperate to insert a supplement into the folder at each alternate revolution of said cutting and collecting cylinder.

3. The combination with a folder having a cutting and collecting cylinder, of a cylinder adjacent, and in position to deliver to, said cylinder but running at half the surface speed thereof and arranged to deliver a printed product to said cutting and collecting cylinder at each alternate revolution of said last mentioned cylinder.

4. The combination with a folder having a cutting and collecting cylinder, and a folding cylinder, of a cylinder adjacent, and in position to deliver to, the cutting and collecting cylinder but running at half the surface speed thereof and arranged to deliver a printed product thereto at each half revolution of said adjacent cylinder, said adjacent and folding cylinders being of the same diameter.

5. In a folder the combination with a folding and a cutting cylinder running at the same surface speed, the diameter of the folding cylinder being twice that of the cutting cylinder, of another pair of cylinders having the same relations and sizes as said folding and cutting cylinders respectively but run-

ning at half their speed, the larger of the two being in position to deliver sheets to said cutting cylinder.

6. The combination with a folding mechanism having a cutting cylinder, of a cutting cylinder and a carrying cylinder arranged to deliver to the cutting cylinder of the folding mechanism, and means for running said cutting and carrying cylinders at half the surface speed of the folding mechanism.

7. The combination with a folding mechanism having a cutting cylinder, of a cutting cylinder and a carrying cylinder arranged to deliver to the cutting cylinder of the folding mechanism, means for running said cutting and carrying cylinders at half the surface speed of the folding mechanism, and means for applying a line of paste to the printed product while on the carrying cylinder.

8. The combination with a main printing press and a supplement printing press having its main printing couple shaft coupled to the end of the printing couple shaft of the main press, of a folder arranged with its main shaft coupled to the printing couple shaft of the main press, so the three machines have their main shafts coupled together in axial alignment.

9. The combination with a main printing press and a supplement printing press operating on a narrow web and having its main shaft coupled to the end of the shaft of the main press, of a folder arranged with its main shaft coupled to the shaft of the main press, so the three machines have their main shafts coupled together in axial alignment, the folder having a former, means for directing the web from the main press to the folder over said former, means for directing the narrow web around the former, and a cutting couple for receiving the web from the supplement press and delivering the sheets to the folder.

In testimony whereof I have hereunto affixed my signature.

HENRY A. WISE WOOD.
